Patented Apr. 13, 1886.

UNITED STATES PATENT OFFICE.

GEORGE E. BOVEE AND SIGMUND BELMONT, OF NEW ORLEANS, LA.

CIGAR-BUNCHING MACHINE.

SPECIFICATION forming part of Letters Patent No. 339,850, dated April 13, 1886.

Application filed June 12, 1884. Renewed January 7, 1885. Serial No. 187,905. (Model.)

To all whom it may concern:

Be it known that we, GEORGE E. BOVEE and SIGMUND BELMONT, of New Orleans, in the parish of Orleans, and in the State of Louisiana, have invented certain new and useful Improvements in Cigar-Bunching Machines; and we do hereby declare that the following is a full, clear, and exact description thereof, reference being had to the accompanying drawings, in which—

Figure 1 shows a perspective view of our machine. Fig. 2 is a sectional view of the same on line $x-x$ of Fig. 1. Fig. 3 is a perspective view of our machine with the hopper-frame and the top of the slide-box removed. Fig. 4 is a detail plan of the forward end of the slide with the belt removed. Fig. 5 is a detail view of the forward end of the machine, showing the binder in position to be wrapped around the tobacco; Fig. 6, a detail vertical sectional view showing the parts in position as when the bunch is being made, and Fig. 7 a detail perspective view of the apron-roller-supporting rod and the nuts thereon; Fig. 8, a detail sectional view showing the operation of the belt and slide in making the bunch.

Letters of like name and kind refer to like parts in each of the figures.

The object of our invention is to provide an improved bunching machine for cigars; and to this end it consists in the construction, arrangement, and combination of parts, as hereinafter described, and more specifically pointed out in the claims.

In the drawings, A designates the base of our machine, which consists of the two side bars, B B, which are attached to and project above the bottom board, B'. This board, as shown, is in two parts, b b', between the ends of which is the transverse slot or space C, into which the belt, to be hereinafter described, can be forced down to form a pocket to receive the tobacco to be rolled and compressed. The part b of the bottom board, B', extends forward beyond the ends of the side bars, B B, which near their forward ends are recessed on their inner sides at D D. The ends of the recesses are beveled, as shown at d d.

Upon the board B', and between the bars B B, is the reciprocating slide E. Its sides are formed with the longitudinal grooves E' E'.

To keep it down in place as it slides, the strips E² E², shaped on their inner sides to fit the grooves E' E', are placed between the sides 55 of the slide and the bars B B, and are fastened in place by means of screws e, passing through the said side bars of the frame. The grooves in the slide are preferably made V-shaped in cross-section. Wear between the strips and 60 sides of the grooves in the slide can be taken up by forcing the strips inward by means of the screws.

The upper face of the slide E is provided with a longitudinal line or series of recesses, 65 e' e', the rear ends of which are abrupt and vertical, while their bottoms slope upward from the rear to their forward ends. With the recesses of this shape, a series of ratchet-teeth is formed in the slide, the tops of which are flush 70 with the upper face, e², of the slide.

To the forward end of the slide is attached the metal plate e³, which extends up in front of the slide and is then bent outward and forward on a plane with the top of the slide. A 75 metal plate, e⁴, is let into the top of the slide, near its forward end, and to this is hinged the rear end of a plate, e⁵, which is attached to or formed in one piece with the flat bar F, which extends across the end of the slide and beyond 80 the side bars, B B, being cut away at f f to form recesses up into which the bars project.

The lower side or edge of the bar F, when it is moving down on its hinge, stands close to the upper surface of the bottom board, b, 85 in front of the slide end. The upper horizontal portion of bent plate e³ serves as a stop to limit the downward movement of the bar. To the forward upright face of the bar is fixed the plate F', which stands parallel to and a 90 slight distance from its face. Through the space between the bar and plate passes the belt G, which is attached at one end to the forward end of board b, as shown, and extends up between the bar F and plate F', over the top of 95 the bar, and rearward below and around a roller, G', to which its rear end is fastened. This roller is supported on a stationary rod or shaft, H, in turn supported in standards I I, through which it passes on either side. 100 The ends of the shaft are screw-threaded, as shown, and upon them are thumb-nuts h h, which can be screwed up against the sides of the standards. When they are screwed up

5 tight, they cause the roller to be bound between the standards, so that it cannot be re-
volved by a pull on the belt G. The amount of slack in the belt between the roller and the
point of its attachment to board b can ob-
viously be readily adjusted by loosening the
nuts, turning the roller in the desired direc-
tion, and then tightening up the nuts again.

10 As the amount of slack in the belt deter-
mines the depth and size of pocket or bight
which can be made in the belt by forcing it
down into the slot or space C in the bottom of
the slide-frame, and the amount of compres-
sion of the tobacco to be bunched for a cigar
15 of a given size, an adjustment for the belt such
as we have shown and described is especially
desirable.

20 To the sides of standards I I, which are at-
tached to the tops of side bars, B B, are fast-
ened the metal plates K K, which have verti-
cal arms K' K', extending up above the stand-
ards, with their front edges in a vertical plane
just back of shaft H.

25 Upon the top of the bars B B is fastened the
board L, forming a cover for the slideway. In
standards L' L', attached to the side of this
board, is journaled the rock-shaft M, to which
is attached the rear end of arm M', carrying
30 at its forward end the hopper-frame M², which
rests upon the tops of standards I I. This
hopper-frame carries a hopper, N, and a feed-
roller, N', at the discharge end thereof. This
roller has a longitudinal recess, O, cut in it of
35 the length of the discharge-opening of the hop-
per, and of a depth sufficient to receive the
requisite amount of tobacco from the hopper.
Attached to the outer ends of the feed-roller
shaft are the crank-handles N² N'. Stop-pins
40 P P on the hopper-frame limit the backward
throw of the handles, stopping them at such
a point that the recess O will be on the upper
side of the roller and in position to receive its
charge from the hopper.

45 The hopper and feed-roller are so situated
that when said roller is turned forward and
downward it will discharge the contents of its
recess onto the depressed portion of belt G in
the space C. To insure that the recess O shall
50 receive a full charge of tobacco from the hop-
per, we give said hopper a number of vertical
vibrations or shakes as the slide E travels back
after a bunch has been formed. To give these
vibrations to the frame to jar the tobacco down
55 in the hopper, we pivot to the arm M', which
carries the hopper-frame, the dependent pawl
R, which engages the ratchet-shaped depres-
sions in the slide. It is so pivoted or hinged
to the arm that it cannot swing backward be-
yond a vertical line, but can swing freely for-
60 ward and upward. With this arrangement, as
the slide moves forward the lower end of the
pawls will ride over the teeth, swinging up-
ward as they pass beneath it; but when the
slide is forced backward its lower end will ride
65 up over the inclined bottoms of the recesses,
raising the arm M', and will drop down into

the next recess, being forced downward by the
weight of the hopper and frame. Thus a series
of sharp jars will be given to the hopper and
its contents and the recess O in the feed roller
70 will be fully charged. The vertical arms K' K'
of the plates K K act to steady the frame in
its movements.

75 The operation of our machine is as follows:
The slide is pushed back to its limit, so that
the belt-bar F is just back of the space or
opening C in the bottom of the slide-frame.
The belt is then pressed down into this space,
80 forming a depression or pocket to receive
the charge of tobacco for the bunch from the
feed-roller. The roller is then turned and
the tobacco dropped down into the depres-
sion in the belt. The slide is then pulled
forward by the operator pulling upon the ex-
tended ends of the bar F. The belt will thus be
85 folded forward over the tobacco, which, as the
bar is moved farther forward, will be entirely
inclosed in the fold of the belt. As the move-
ment of the bar and slide is continued the
bight or pocket in the belt is moved outward
90 and forward and rises up over the forward
edge or side of the space or opening C in the
bottom plate, b, into the space behind the bar
F, below the upper horizontal portion of plate
e³ on the front end of the slide E, as shown
95 best in Fig. 8. As the bar F is pulled for-
ward the belt must of course pass up between
the front face of the bar and the plate F'
thereon and over the top of the bar, or, to ex-
press it more truly, the bar and plate must
100 move along the belt, as the rear end of the lat-
ter is attached to the roller G', as described, and
cannot be pulled along. The bight or pocket
in the belt containing the charge of tobacco
105 and situated in the space inclosed by the plate
e³, the bar F and the bottom b of the slideway
are by the movement of the bar and slide car-
ried along over the slideway bottom. As the
bight is thus caused to move forward along
110 the belt, the tobacco in the bight is rolled over
and over by the movement of the belt with re-
lation to the bar and slide in the same way as
it would be if the slide and bar remained sta-
tionary and the belt were pulled out toward its
115 rear end. Any thin sheet of tobacco, paper, or
other material lying upon the belt in front of
the bar F and slide will then, when the bight
or pocket in the belt reaches it, pass with the
belt down under and over the roll of tobacco
120 in the pocket, and as the rotation of such roll
is kept up by the passage of the belt will be
wrapped around the roll, as shown in Fig. 8.

125 As the bar F is hinged by means of plate e³
to the end of the slide, the amount of compres-
sion of the tobacco can be regulated at will by
raising or pressing down upon said bar. Be-
fore the roll or bunch of tobacco reaches a
line between the rear ends of the recesses in
the side bars, B B, a binder is laid on the belt
130 between such recesses, with its ends extending
out into them, as shown in the drawings.

If the binder does not lie quite smoothly

on the belt, the bar F can be raised slightly to pass over its edge. If the movement of the bar be continued, the bunch of tobacco within the fold of the belt is rolled over the edge of the binder, and said binder will be wrapped tightly around it. The inturned ends of the recesses will turn or fold the ends of the binder inward to inclose the tobacco. This is especially desirable where the tobacco is fine or granulated.

Upon the belt, forward of the recesses in the side bars, can be placed a paper cover, T, into which the tobacco-bunch with its binder is rolled, just as the tobacco was first rolled into the binder. The edge of the cover T is to be pasted, so that as the cover is rolled around the bunch it will be securely fastened thereon. The bunch is then complete and ready to be placed in a mold, from which, after proper pressure, it is taken and the paper slipped off or removed to make it ready to be rolled and made into a cigar.

With a change in size only our machine is obviously suited for the manufacture of cigarettes, as well as cigar-bunches.

Instead of making a series of ratchet-shaped depressions in the upper face of the slide, a series of ratchet-teeth or projections could be placed or formed on the slide without departing from our invention.

Our belt we call a "stationary" one to distinguish it from the endwise-moving ones used in other cigar-bunch-making machines. The term as used by us to so distinguish our belt from the others then only means that the belt has no endwise movement, not that it is inflexible or incapable of rising and falling and bending.

The belt, as described and shown, is entirely flexible, and is loose everywhere except at its ends, which are attached to stationary parts of the machine.

Having thus fully set forth the nature and merits of our invention, what we claim is—

1. In combination with the bottom of the slideway provided with a transverse opening, the belt attached at each end to some fixed portion of the frame, and loose between such ends, so that a bight or pocket can be formed therein, the slide resting upon and having its front end extending squarely across the bottom of the slideway, and the bar on the front end of the slide engaging the under or rear side of the belt, and so arranged on or attached to the slide as to leave a space between it and the slide end, substantially as and for the purpose described.

2. In combination with the slideway having its bottom provided with a transverse opening or recess, the slide, the transverse bar hinged to the front of the slide, so as to leave a space between it and the slide end, and having its ends extended outward beyond the slideway to form handles, which can be grasped by the hands, and the belt fixed at one end at or near the forward end of the slideway, passing back over the front of the bar, and made fast at its

rear end above the slide, substantially as and for the purpose described.

3. In a cigar-bunch-making machine, the way along which the bunch is moved as it is rolled, having in its sides at or near their forward or outward ends opposite recesses with inwardly-inclined forward or outer ends, substantially as and for the purpose set forth. 75

4. In a cigar-bunch machine, in combination with a stationary belt, a slide, a bar hinged to the forward end of the slide and provided with a plate, between which and the bar passes the belt, and side bars on each side of the belt formed with recesses having inwardly-inclined forward ends, substantially as and for the purpose described. 75

5. In a cigar-bunch-making machine, the beltway, the stationary belt, means, substantially as described, for causing a bight or pocket in the belt to move along the same, and the bars at the sides of the way provided with recesses to receive the end of the binder placed on the belt, which have their forward ends inclined inward, so as to fold the ends of the binder as it is wrapped around the tobacco in the bight of the belt, substantially as and for the purpose described. 85

6. In combination with the stationary belt of a cigar-bunch machine, the adjusting device therefor, consisting of a roller to which is attached one end of the belt, a shaft extending through the roller, and suitable standards on the frame, and thumb-nuts on the outer ends 100 of the shaft adapted to be screwed up against the standards to bind the roller between the latter and prevent its rotation, substantially as shown and described. 95

7. In a cigar-bunch-making machine, the slide provided with a series of teeth or projections on its upper side, in combination with the movable hopper-frame provided with a downwardly-projecting pawl or arm engaging the teeth or projections on the slide, whereby as the slide is moved the hopper will be raised and let fall, substantially as and for the purpose set forth. 110

8. In a cigar-bunch-making machine, the hopper-frame carried on a pivoted bar, in combination with the slide formed with a series of ratchet-shaped depressions in its upper face, and the pawl pivoted to the bar and adapted to engage these depressions and the ratchet portions of the slide between them as the slide is moved back, so as to raise and let fall the bar and frame, substantially as and for the purpose described. 115

9. In a cigar-bunch-making machine, in combination with the bar pivoted at its rear end and carrying the hopper-frame on its front end, the pawl pivoted to the lower side of the bar, so that it cannot swing back beyond a vertical line, but can swing forward and upward, and the belt-operating slide provided with a series of ratchet-shaped teeth having their abrupt faces toward the forward end of the slide, substantially as and for the purpose described. 125

10. In combination with the hopper, the feed-roller provided with the charge-receiving recess, the crank-arms attached to the roller, and the stop-pins on the frame to stop the arms when the recess in the roller is just below the hopper-bottom, substantially as shown and described.

In testimony that we claim the foregoing we

have hereunto set our hands this 7th day of April, A. D. 1884.
